United States Patent Office

Des. 206,751
Patented Jan. 24, 1967

206,751

BUILDING

Meryl Lynn Stoddard, Flint, Mich.
(Box 322, Scottsdale, Ariz. 85251)

Filed Mar. 16, 1966, Ser. No. 1,486

Term of patent 14 years

(Cl. D13—1)

FIG. 1

FIG. 2

FIG. 3

I claim:

The ornamental design for a building, substantially as shown.
